SAFETY-RAZOR HANDLE

Meyer J. Shnitzler, Brookline, Mass.

Application November 17, 1953, Serial No. 27,643

Term of patent 14 years

(Cl. D22—3)

To all whom it may concern:

Be it known that I, Meyer J. Shnitzler, a citizen of the United States of America, residing at Brookline, Massachusetts, have invented a new, original, and ornamental Design for a Safety-Razor Handle, of which the following is a specification, reference being had to the accompanying drawing, forming a part hereof, wherein:

Fig. 1 is a front elevational view, on an enlarged scale, of a safety-razor handle embodying my new design.

Fig. 2 is a top plan view; and

Fig. 3 is a bottom plan view thereof.

I claim:

The ornamental design for a safety-razor handle, substantially as shown.
